UNITED STATES PATENT OFFICE.

ETTORE CALONE AND FERDINAND DANTON, OF NEW YORK, N. Y.; SAID DANTON ASSIGNOR TO MAXIME E. BOURGEOIS, OF SAME PLACE.

BROILING-RANGE.

SPECIFICATION forming part of Letters Patent No. 360,372, dated March 29, 1887.

Application filed July 12, 1886. Serial No. 207,756. (No model.)

To all whom it may concern:

Be it known that we, ETTORE CALONE and FERDINAND DANTON, residents of the city, county, and State of New York, have invented 5 certain new and useful Improvements in Broiling-Ranges; and we do hereby declare that the following is a full and exact description thereof, reference being had to the accompanying drawings, and to the letters of reference 10 marked thereon, making a part of this specification.

Our invention relates to ranges specially adapted for broiling, and has for its object to so construct the range as that the smoke or 15 vapors from the broiling meats shall be drawn by a downward draft through the bed of coals, and be thereby consumed, and to prevent, consequently, the liability of the meats to burn and catch fire, obviate all smoke or odor 20 therefrom, and relieve the cook from the need of giving constant attention thereto, as well as from exposure to the intense heat of the fire to which an attendant upon an ordinary form of broiler is subjected.

It has also for its object the conversion of 25 the broiling-range into an ordinary stove with facility, so that the apparatus may be used for cooking in any desired manner. These objects are attained by the combination, in 30 manner substantially as hereinafter described, with the fire-box and ash-pit of the stove or range, of a draft-chamber and flue at the rear thereof, communicating directly with the chimney, and also, through suitable openings governed 35 by dampers or valves, both with the ash-pit below the grate and with the upper portion of the fire-box above the grate, whereby the draft ordinarily created from the ash-pit upward through the fuel on the grate into the 40 fire-box and out from above the fire to the chimney may be reversed, and caused to pass from the top of the stove downward through the fire-box and through the burning fuel on the grate, and thence from under the fire out 45 to the chimney, and also, by the combination, with such a range or stove, of a sliding top adapted to cover and uncover the fire-box in manner as hereinafter set forth.

In the accompanying drawings, Figure 1 is 50 a view in perspective of our improved range with the sliding top moved back in readiness

for the use of the range in broiling, and Fig. 2 is a central vertical section thereof in the line *xx* of Fig. 1.

A represents the outer casing of the range; 55 B, the fire-box, which is lined with fire-brick C in the customary manner, so far as its construction admits thereof.

D is the bottom grate, upon which the fuel rests; E, the ash-pit; F, the front door opening 60 into the ash-pit and provided with a draft-damper, G.

In the foregoing features of its construction the range does not differ essentially from many forms of stoves and ranges in common use, and 65 it may be modified in these particulars, as well as in the proportions of its parts.

H represents a draft-chamber or flue adapted to establish direct communication, when required, between the ash-pit E and the discharge-flue or smoke-pipe I of the stove or range, by which it is connected to a chimney. This draft-chamber or flue H is separated from the fire-box B and ash-pit E by a partition, 70 preferably extending from the top plate to the bottom plate of the stove and from side to side thereof, and it is inclosed and completed by the rear plate of the stove, and by its top, side, and bottom plates, extended for the purpose, as shown in the drawings. 75

The upper portion of the draft-chamber H communicates directly with the smoke-pipe I, and through it with the chimney. It also communicates with the upper portion of the fire-box, near to the top of the stove, by means of 80 an opening, J, in the interposed partition, as shown in Fig. 2, whereby a direct draft may be obtained upward and outward from the ash-pit up through the grate and fire-box to the smoke-pipe I, in the customary manner 85 common to all stoves. This draft-opening J is fitted with a damper-door, a, by which it may be entirely or partially closed, as required.

A second opening is formed in said partition immediately over the grate D, whereby upon 90 closing the ash-pit door and the damper A a draft may be produced from the top of the stove laterally downward through the fire, outward into the chamber H, and to the smoke-pipe I; and this opening is fitted with a perforated 95 plate or grating, K, and also with a damper-door, b, by which it is opened or closed 100

at pleasure. A third extended opening, L, is formed in the partition between the draft-chamber H and the ash-pit E, below the grate-bars D, whereby a downdraft may be created from 5 above the bed of fuel on the grate-bars down through the grate-bars and ash-pit, and thence outward through the chamber H to the smoke-pipe I. This third independent opening is also fitted with a controlling-damper, e, opening into the chamber H, as illustrated in Fig. 2.

A detachable broiler-grating, M, is fitted to rest over the top of the fire-box B, immediately below the top of the range.

The whole top or cover N of the range is 15 movable, and is mounted to slide in suitable ways from front to rear, so as to wholly uncover the fire-box B and broiling-grate H, when required. When pushed back, the top is supported partly upon the top of the compartment 20 H and partly upon brackets P P, projecting rearward from the stove.

Access to the compartment H, for the purpose of cleaning it &c., is provided by means of a side door, R. (See Fig. 1.)

25 In the use of the range, the fuel is placed and the fire is kindled in the customary manner in the fire-box B, the coke or coal covering not only the bottom grate, D, but also the rear grating, K. If, now, the range is to be used as 30 a stove, the broiling-grate M is removed and the cover N is drawn forward over the fire-box, while the dampers b and c are closed and the front damper, G, or front door, F, of the range is opened. The draft is now carried in 35 the usual manner from the opening at G or F through the ash-pit E, upward through the body of fuel lying on the grate D, and out to the chimney through the upper draft-opening, J, by whose damper a the consumption of fuel 40 and intensity of the fire may be regulated.

When the range is to be used for broiling, which is the chief end of its construction, the cover N is pushed back, as shown in the drawings, the broiling-grate M is fitted in place, 45 and the upper damper, a, and the lower front door and damper, G, are tightly closed, while either or both of the dampers b and c are opened, as the condition of the fire or the character of the article to be cooked may require. The draft will now pass from above 50 the broiling-grate M, down through the body of coals upon the grate D, and out laterally through the openings in the grating-bars K, and also down between the grate-bars D into 55 the ash-pit, and through the opening L into the draft-chamber H, and through it to the flue I and chimney. This downward draft through the fire will carry with it the smoke from the cooking meat and from the drippings 60 of fat therefrom into contact with the incandescent fuel on the grate, to be thereby consumed, instead of passing out into the room, while this downward draft of air will prevent

also the heat from the fire from radiating upward into the face and eyes of the cook when 65 in attendance.

Where the bed of coals is of but comparatively slight depth, the damper b is closed, as well as the upper damper, a, so that the draft is directly wholly downward through the 70 grate D.

We claim as our invention—

1. The combination, with the fire-box, grate, and ash-pit in a stove or range, of a transverse partition interposed between the rear of 75 the fire-box or ash-pit and the rear wall of the stove or range, to form a draft-chamber extending from top to bottom thereof, communicating by means of draft-openings in said partition both with the upper portion of the 80 fire-box and with the ash-pit, dampers controlling and closing, respectively, each of said openings, and a smoke pipe or flue to connect the upper end of the draft-chamber with a chimney, all substantially in the manner and 85 for the purpose herein set forth.

2. The combination, with the fire-box, grate, and ash-pit in a stove or range, of a transverse partition interposed between the rear of 90 the fire-box or ash-pit and the rear wall of the stove or range, to form a draft-chamber extending from top to bottom thereof, communicating by means of draft-openings in said 95 partition with the upper portion of the fire-box, the lower portion of the fire-box just above its bottom grate-bars, and with the ash-pit, a grate fitted in the central opening, dampers closing and controlling, respectively, each of the openings, and a smoke pipe or flue to connect the upper end of the draft-chamber 100 with a chimney, substantially in the manner and for the purpose herein set forth.

3. The combination, with the fire-box, grate, and ash-pit in a stove or range, of a transverse partition interposed between the rear of 105 the fire-box or ash-pit and the rear wall of the stove or range, to form a draft-chamber extending from top to bottom thereof, communicating by means of draft-openings in said partition both with the upper portion of the 110 fire-box and with the ash-pit, dampers controlling and closing, respectively, each of said openings, a smoke pipe or flue to connect the upper end of the draft-chamber with a chimney, and a movable cover adapted to slide 115 back and forth over the top of the fire-box, all substantially in the manner and for the purpose herein set forth.

In testimony whereof we have signed our names to this specification in the presence of 120 two subscribing witnesses.

ETTORE CALONE.

FERDINAND DANTON.
